UNITED STATES PATENT OFFICE.

GUY V. SPARLIN, OF TAMPA, FLORIDA.

PNEUMATIC HORN.

Application filed October 24, 1925. Serial No. 64,609.

This invention relates to pneumatic horns, and has more particular reference to a device of this kind embodying a reed and pneumatic means for causing vibration of the reed so as to produce sound for amusement or signalling purposes.

The primary object of the invention is to provide a horn of the above kind embodying a removable sound amplifier and in which means is provided for varying the tone of the sound produced by the horn or for causing the device to emit a sound resembling greatly that produced by a whistle upon removal of the sound amplifier.

15 A further object of the invention is to provide a horn of the above kind wherein the sound produced may be varied for the purpose above mentioned through the medium of adjusting means for the reed and a removable sound amplifier carried by the body which supports the reed.

With the above general objects in view, and others that will become apparent as the nature of the invention is better understood, 25 the same consists in the novel form, combination and arrangement of parts hereinafter more fully described, shown in the accompanying drawing and claimed:

In the drawing, wherein like reference 30 characters indicate corresponding parts throughout the several views.

Figure 1 is a view partly in longitudinal section and partly in elevation, of a horn constructed in accordance with the present 35 invention.

Figure 2 is an enlarged transverse section taken substantially upon line 2—2 of Figure 1,

Figure 3 is a view similar to Figure 2 taken upon line 3—3 of Figure 1, and

Figure 4 is a view similar to Figure 3 taken substantially upon line 4—4 of Figure 1.

Referring more in detail to the drawing, 45 the present invention embodies a cylindrical or elongated hollow body 5 which has a removable cap 6 on one end. This cap has a central opening in which is removably secured the end of a reed tube 7. The inner 50 end of the reed tube 7 is cut away at one side to provide an opening with which is associated the reed 8 which is preferably of metal and of a resilient nature so as to normally yieldingly flex away from the tube 7.

55 Threaded transversely through a side of the body 5 is a set screw 9 which has relatively

fine threads and which is so arranged as to have its inner end bear against the reed 8 whereby, upon adjustment of said screw 9 the reed 8 may be flexed laterally toward the adjacent end of the tube 7 or may be allowed to flex away from the same as desired. A lock nut 10 is carried by the set screw 9 and arranged to bear upon the exterior surface of the body 5 for locking the adjusting screw 60 9 in any desired adjusted position. Removably carried by the cap 6 in which the tube 7 is mounted, is a sound amplifier 11 preferably of the tapered form shown. This sound amplifier may be threaded onto the cap 6 as shown, although other detachable means for securing the same on the cap may be employed if desired. When air is blown into the outer or inner end of the body 5 the reed 8 will be caused to vibrate, and by 65 properly adjusting the screw 9 the tone of the sound emitted may be varied as desired. When the screw 9 is adjusted to a predetermined position and the sound amplifier 70 11 is in place upon the cap 6, the device will 75 emit a sound greatly similar to horns used as signals upon vehicles or for various other purposes. On the other hand, by adjusting the screw 9 to another position the reed will 80 be so modified in action that when the 85 amplifier 11 is removed from the cap 6 the sound emitted will greatly resemble that produced by a whistle.

In order to force air into the inner end of the body 5, I prefer to provide an elastic 90 bulb 12 having one end connected by a flexible conduit or tube 13 to the inner end of the body 5 and having an inlet at its other end controlled by an outwardly seating check valve as generally indicated at 14. It will 95 thus be seen that when the bulb 12 is compressed air will be forced into the body 5 so as to act upon the reed 8 and cause the horn to emit a sound. When this takes place the check valve at 14 is seated so as to prevent the escape of air from the bulb except through the tube 7, and upon release of the bulb the valve will be unseated so as to permit the entrance of more air into the bulb. This provides a means for supplying air to 100 the body which will eliminate the necessity of applying lips to a mouthpiece or the like as is necessary with many toy horns heretofore devised. The connection of the tube 13 with the bulb and the body is preferably a 105 detachable one so as to permit the insertion of additional lengths of tubing in case it is

desired to actuate the bulb 12 from a point remote from the point at which the body 5 is positioned. These detachable connections are generally indicated at 15 and embody, 5 as shown, studs of hollow form through which the air will pass. One of these hollow studs is preferably threaded in a central opening of a cap 16 removably secured on the other end of the body 5.

10 It will be seen that the screw 9 furnishes means for fine adjustment of the reed so that a great number of small variations in sound may be provided for or obtained. It is also apparent that the reed tube may be readily 15 removed from the body with the cap 6 and then removed from said cap to permit substitution of a new reed tube if found necessary or desirable. The new reed tube may be of a size or character different from that of 20 the original for providing a further variation of sound, or it may be the same as the original and required by reason of breakage of or damage to the original.

Minor changes may be made without departing from the spirit and scope of the 25 invention as claimed.

What I claim as new is:

A horn of the character described com-

prising a sound amplifier having a constricted end, a cap body comprising a cylindrical member having external threads throughout substantially half its length and designed to connect the body to the constricted end of the amplifier, said cap having a pair of concentrically arranged longitudinally extending aligned bores, one of greater diameter than the other and each provided with screw threads throughout its length, the bore of smaller diameter being in that end of the body having the external threads thereon, said bore of smaller diameter opening into the aligned other bore, a reed tube having one end threaded into said small bore, a reed carried by said tube and having one end fixed thereto, the other end 45 being directed toward the forward end of the tube, an elongated tubular body encasing the projecting portion of said reed and having one end journaled into the bore of greater diameter, a cap member threaded 50 upon the other end of said tubular body, and means for forcing air through said cap member, substantially for the purpose set forth.

In testimony whereof I affix my signature.

GUY V. SPARLIN.
